UNITED STATES PATENT OFFICE

JOHN H. DOMKEE, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

SLIDE BUCKLE

Application filed September 4, 1930. Serial No. 479,721.

This invention relates to that class of buckles known as slides and used for adjusting the length of straps, webbing, and the like, without penetrating the material, and the objects of the invention are to provide a reversible slide buckle having an intermediate bar formed with spaced humps projecting in opposite directions along planes perpendicular to the plane of the buckle; and to provide a slide buckle of said type in which the initial cost of tooling for its manufacture is the minimum. With these and other objects in view as may become apparent from the within disclosures, the invention consists not only of the particular form herein pointed out and illustrated in the drawing, but readily admits of certain modifications within the scope of what hereinafter may be claimed.

The character of the invention may be best understood by reference to one illustrative device embodying the invention and illustrated by the accompanying drawing in which the Figure 1 is an upright elevation of the device; the Figure 2 is a top view of the device; and the Figure 3 is a detail view in perspective of a member of the device; the Figure 4 being a modification of that member illustrated in perspective.

The device about to be described is an improvement of the device disclosed in the Patent No. 1,762,263, issued to the same petitioner June 10, 1930. While the device is illustrated as made of wire, it may be partially or wholly stamped from sheet metal, but as illustrated the slide buckle is made in two pieces of which one piece is of wire bent to form a rectangular frame having the top bar 1, the lower bar 2, and the side bars 3 and 4. The other piece is a flat wire intermediate bar 5 longitudinally split to provide the strands 6 and 7 integrally connected at both ends, the extremities 8 and 9 of the bar 5 beyond the strands being looped around the side bars 3 and 4, respectively, for either a fixed or sliding engagement upon the buckle-frame. In the forming of the bar 5, the strands 6 and 7 are independently made in undulating form with relatively staggered high points projecting out of the plane of the buckle, each strand being immediately bent, as at 10 and 11, in opposite directions out of said plane, and angularly bent and returned, as at 12 and 13, relatively crossed, as at 14, angularly rebent and returned, as at 15 and 16, and recrossed, as at 17, and so throughout the length of the strands 6 and 7 thereby alternately providing spaced peaked humps, as for instance at 13 and 15, projecting in one and the same direction out of said plane, and, as at 12 and 16, projecting out of said plane in one and the same direction opposite to that of the humps 13 and 15, as best illustrated by the Figure 3, and thus providing an indestructible slide buckle of which the distance of the projections out of said plane in one direction equals the distance of the projections out of said plane in the opposite direction, the slide buckle therefore being reversible in use in that the buckle may be turned around from the position illustrated by the Figure 1 so that the upper bar 1 may be in the position of the lower bar 2, or so that the side bar 3 and the opposite side bar 4 may each occupy the position of the other. It is therefore apparent that the undulated strands 1 and 2 cooperate to form spaced humps 13 and 15 and like humps projecting from the buckle plane in one direction, and spaced humps 12 and 16 and like humps projecting from said plane in the other direction to provide an acute detour for a strap threaded into the slide buckle in either of the two ways already known to the art. The intermediate bar 5 may be mounted upon the side bars 3 and 4 loosely for a sliding engagement thereon or it may be rigidly secured thereto.

The Figure 4 illustrates a modified form in which the strands 1 and 2 of the intermediate bar 5 may be formed by immediately bending the strands, as at 10A and 11A, and then by further bending so that one strand provides humps for projection out of the plane of the buckle in a particular direction, as at 12A and 15A, and the other strand provides humps for projection out of said plane in the opposite direction, as at 11A and 16A.

I claim:

1. A reversible slide buckle comprising a frame having an upper bar and a lower bar

connected by side bars; an intermediate bar extending from one side bar to the other side bar and longitudinally split, throughout its middle portion, into strands integrally connected at both ends; and peaked humps provided by both strands, the peaked humps of one strand alternating with the peaked humps of the other strand to provide spaced peaked humps projecting out of the plane of the buckle in one direction and also spaced peaked humps projecting out of said plane in the other direction.

2. A reversible slide buckle comprising a frame having an upper bar and a lower bar connected by side bars; an intermediate bar mounted upon the side bars and longitudinally split, throughout its middle portion, into strands integrally connected at both ends; and peaked humps provided by both strands, the peaked humps of one strand alternating with the peaked humps of the other strand to provide spaced peaked humps projecting out of the plane of the buckle in one direction and also spaced peaked humps projecting out of said plane in the other direction.

3. A reversible slide buckle comprising a rectangular frame having an upper bar and a lower bar connected by side bars; and an intermediate bar mounted upon the side bars and longitudinally split, throughout its middle portion, into two strands integrally connected at both ends and first bent out of the plane of the buckle, each in opposite directions, and each strand being further bent, relatively crossed and recrossed to alternately provide spaced peaked humps projecting from said plane in both directions.

4. A slide buckle of rectangular form having an upper bar, a lower bar, and side bars; and an intermediate bar mounted upon the side bars and longitudinally split, throughout its middle portion, into two strands integrally connected at both ends, the strands being angularly bent at intervals, the angular bends of one strand alternating with the angular bends of the other strand to provide spaced peaked humps projecting out of the plane of the buckle in opposite directions.

5. A slide buckle of rectangular form having an upper bar, a lower bar, and side bars; and an intermediate bar mounted upon the side bars and longitudinally split, throughout its middle portion, into two strands integrally connected at both ends, each strand being immediately bent at one end in opposite directions out of the plane of the buckle, and each strand being angularly bent and returned, relatively crossed, angularly rebent and returned and recrossed, repeatedly, each strand thus providing spaced peaked humps extending out of the said plane in both directions.

6. A slide buckle of rectangular form having an upper bar, a lower bar, and side bars;

and a flat intermediate bar mounted upon the side bars; a slot longitudinally provided by a middle portion of the intermediate bar to divide the bar into two strands integrally connected at both ends, each strand being immediately bent at one end in opposite directions out of the plane of the buckle, and each strand being angularly bent and returned, relatively crossed, angularly rebent and returned and recrossed, repeatedly, each strand thus providing spaced peaked humps extending out of said plane in both directions.

7. A slide buckle of rectangular form having an upper bar, a lower bar, and side bars; an intermediate bar extending from one side bar to the other side bar and longitudinally split, throughout its middle portion, into strands integrally connected at both ends; and peaked humps provided by both strands which together provide spaced peaked humps projecting out of the plane of the buckle in opposite directions.
